(57) **CLAIM**

The ornamental design for a compact disc case, as shown and described.

DESCRIPTION

FIG. 1 is a perspective view of a compact disc case showing our design;

FIG. 2 is a side view thereof, the opposite side being identical thereto;

FIG. 3 is a top plan view thereof;

FIG. 4 is a front view thereof;

FIG. 5 is a rear view thereof;

FIG. 6 is a top plan view thereof with the retaining strap removed; and,

FIG. 7 is a bottom plan view of the compact disk case shown in FIG. 1.
